DESIGN FOR A TEXTILE FABRIC OR SIMILAR ARTICLE

Edmond P. Bixer, New York, N. Y.

Application April 24, 1940, Serial No. 91,918

Term of patent 3½ years

all whom it may concern:
Be it known that I, Edmond P. Bixer, a citizen of United States of America, residing at New York,
the county of New York and State of New York,
have invented a new, original, and ornamental design for a Textile Fabric or Similar Article, of which the following is a specification, reference being had to the accompanying drawing, con-tuting a part thereof.

The figure is a plan view of a textile fabric
showing my new design.

I claim:

The ornamental design for a textile fabric or similar article, as shown.

EDMOND P. BIXER.
